COIN SELECTOR

William H. Rowe, New York, N. Y.

Application December 5, 1933, Serial No. 700,984
Renewed October 2, 1935

6 Claims. (Cl. 194—101)

This invention relates to improvements in coin selecting devices which may be used with coin actuated mechanisms.

The general object of the invention is to provide an improved coin selector device which will separate spurious coins, slugs or other objects from good coins of the denomination intended to actuate the device with which it is associated. Other objects and the advantages of this invention will be apparent from the following description taken in connection with the accompanying drawings wherein:

Fig. 1 is a face view of one of the coin selecting units of the device with the cover plate removed; Fig. 2 is a section taken on line 2—2 of Fig. 1; Fig. 3 is a section taken on line 3—3 of Fig. 1; Fig. 4 is a section taken on line 4—4 of Fig. 1; Fig. 5 is a view similar to Fig. 1 of the other coin selecting unit of the device; Fig. 6 is a section taken on line 6—6 of Fig. 5; and, Fig. 7 is a section taken on line 7—7 of Fig. 5; and,

Fig. 8 is an elevation showing a detail.

Referring to the drawings by reference characters I have indicated my improved coin selector generally at 10. The device 10 is especially adapted for use in combination with a coin actuated mechanism, wherein two coins of different denominations are required to actuate the mechanism which in this instance are a dime and a nickel. The present invention is an improvement over that shown in application Serial No. 617,356, filed June 15, 1932, by William L Gilchrist and

William H. Hoofnagle.

As shown the device 10 comprises a nickel selecting unit 12 and a dime selecting unit 13. The nickel selecting unit 12 comprises a base member 14 having a cover plate 15 secured thereto by screws 16 and which is retained in spaced relation to the base 14 by raised portions on the base such as indicated at 17 to form a chamber 18. The base 14 and the cover plate 15 are made of non-ferrous metal and are preferably die cast.

Adjacent the top of the device 14 I provide an entrance raceway 20 which is formed by a pair of spaced rearwardly and downwardly inclined guide portions 21 and 22. The entrance raceway 20 is adapted to direct coins into a forwardly and downwardly inclined raceway 23 which is formed by a pair of spaced guide portions 24 and 25. The raceway 23 is adapted to direct coins into a vertical raceway 26 which on the forward side includes a guide portion 27 which includes a shoulder 27'.

A portion of the bottom of the raceway 23 is formed by an upper face of a bar magnet 28 which at its forward end terminates at the juncture of the raceway 23 and the raceway 26 in a rounded end portion 29. The raceway 26 communicates with a raceway 30 which includes a rearwardly curved section 31 and a straight rearwardly and downwardly inclined section 32. The lower side of the curved section 31 of the raceway 30 is formed by a guide portion 33 and the upper 10 side is formed by a guide portion 34 which has a forward face 34' and the lower portion of the straight section 32 is formed by a guide portion 35. The guide portions 33 and 35 are preferably bevelled downward towards the cover plate as indicated at 36 (see Fig. 2) to urge coins towards a magnet to be presently described.

Good nickels upon leaving the raceway 30 pass through a raceway 37 and enter a vertical exit raceway 38. The bottom of the raceway 37 is 20 formed by a selector device 39 which includes a dividing point 40. The selector device 39 is pivotally mounted on the base 14, as indicated at 40', so that it may be swung and adjusted and is adapted to be firmly retained in an adjusted position by a screw 40'.

Spurious coins upon leaving the raceway 30 fall into a downwardly and forwardly inclined raceway 41 which directs them into a vertical raceway 42. The bottom of the raceway 41 is 30 formed by a guide portion 43 and the forward side of the raceway 42 is formed by a guide portion 44.

Adjacent the juncture of the raceways 23 and 26 I provide a rearwardly and downwardly inclined raceway 45 the top of which is formed by a guide portion 46 and the bottom by a guide portion 47 with the guide portion terminating adjacent the curved portion 29 of the magnet 28. The raceway 23 directs ferrous coins into a downwardly and forwardly inclined raceway 48 one 40 side of which is formed by a guide portion 49 and the other side by a guide portion 50.

Adjacent the lower end of the raceway 48 I 45 provide an aperture 51 in the cover plate 15 (see Fig. 4). Furthermore, adjacent the lower end of the raceway 48 I provide an abutment portion 52 which fits an aperture in the cover plate 15 and which includes an inclined surface 53 which is adapted to direct coins out of the device 12 through the aperture 51 in the cover plate 15.

Intermediate the length of the entrance raceway 20 I provide an elongated aperture 54 in 55

the base 14 and in the raceway 23 I provide a similar aperture 55 in the base.

Adjacent the straight section 32 of the raceway 30 I provide a horse shoe magnet 56, the poles 57 and 58 of which are arranged in holes in a plate 58^a which fits in a slot 58^b in the cover plate 15. The plate 58^a has end ribs 58^c and side ribs 58^d thereon. The poles 57 and 58 are positioned across the raceway 30 at approximately right angles thereto with the faces of the poles and the face of the plate 58^a flush with the inner face of the base 14. Opposite the magnet 56 I provide a similar horse shoe magnet 59, similarly mounted and with the poles 60 and 61 positioned across the raceway 30 similar to the poles of the magnet 56. The faces of the poles 60 and 61 and the plates 58^a thereof are flush with the inner face of the cover plate 15 as clearly shown in Fig. 3. The poles of the magnets 56 and 59 are positioned in opposed relation, that is the north pole of the magnet 56 is opposite the south pole of the magnet 59 and vice versa.

The dime selecting unit 13 like the nickel selecting unit 12 comprises a base 62 having a cover plate 63 thereon which is retained in spaced relation from the base by raised portions on the base such as indicated at 64 to form a chamber 65. The base 62 and the cover plate 63 are made of non-ferrous metal and are preferably die cast. Adjacent the top of the device 13 I provide a rearwardly curved entrance raceway 66 which is formed by a pair of spaced guide portions 67 and 68. The raceway 66 directs coins into a rearwardly and downwardly inclined raceway 69 the top of which is formed by a guide portion 70 and the bottom by a guide portion 71. The raceway 69 directs coins into a raceway 72 which is inclined rearwardly and downwardly at a sharper slope than the raceway 69 and one side of which is formed by a guide portion 73.

Adjacent the juncture of the raceway 69 and the raceway 72 I provide a magnet member 74 the end of which at the juncture of the raceways 69 and 72 is rounded as at 75 and a portion of the magnet 74 adjacent the juncture of the raceways 69 and 72 forms a part of the bottom of the raceway 69, as at 76. The raceway 72 directs coins into a downwardly and forwardly inclined raceway 77 the sides of which are formed by spaced guide portions 78 and 79. The guide portion 79 includes a shoulder 79'.

The raceway 77 communicates with a raceway 80 which includes a forwardly curved section 81 and a straight, forwardly inclined, section 82. One side of the curved section 81 of the raceway 80 is formed by a guide portion 83 and the opposite side by a guide portion 84 and the top of the straight section is formed by a guide portion 85 while the bottom is formed by a guide portion 86. The guide portion 84 of the curved section 81 of the raceway 80 is preferably bevelled towards the cover plate as indicated at 84' (see Fig. 7). Good dimes upon leaving the raceway 80 fall into a forwardly and downwardly inclined raceway 87 which directs them into a vertical exit raceway 88. The bottom of the raceway 87 is formed by a guide portion 99 and the rear of the raceway 88 is formed by a guide portion 100. The front of the raceway 88 is formed by a guide member 101 which is separate from the base 62 and is loosely mounted on the base by rivets 102. By loosely mounting the guide member 101 coins striking this guide member will be prevented from rebounding therefrom over the separating point 125 into the coin chute 103.

Some spurious coins upon leaving the raceway 80 fall into a rearwardly and downwardly inclined raceway 103 which directs them into a vertical exit raceway 104. The bottom of the raceway 103 is formed by a guide portion 105 and the rear of the raceway 104 is formed by a guide portion 106.

Other spurious coins upon leaving the raceway 80 strike a selector device 107 and run down this selector device and fall downward and strike a selector device 108 and are directed into a raceway 103. Each of the selector devices 107 and 108 is pivotally mounted on the base 62 as indicated at 109 and 110 so that they may be adjusted and are adapted to be firmly clamped in adjusted positions by screws 110.

Adjacent the juncture of the raceway 69 and 72 I provide a forwardly and downwardly inclined raceway 112 the top of which is formed by a guide portion 113 and the bottom by a guide portion 114, and a portion of the bottom of the magnet 74 as indicated at 115. The raceway 112 directs ferrous coins into a rearwardly and downwardly inclined raceway 116 the forward side of which is formed by a guide portion 117 and the rear side by a guide portion 118.

Adjacent the straight section 82 of the raceway 80 I provide a horse shoe magnet 120 which is set in a plate 120^a which is similar to the plate 58^a, previously described. The poles 121 and 122 of the magnet 120 are positioned across the raceway 80 at approximately right angles thereto with the faces of the poles flush with the inner surface of the cover plate 63 as clearly shown in Fig. 7. Set into the base 62 opposite the magnet 120 I provide an armature plate 123, the inner face of which is flush with the inner face of the base and the outer face is flush with the outer face of the base.

When the device 10 is operatively assembled the nickel unit 12 and the dime unit 13 are positioned with their respective bases back to back and are retained in this position in any desired manner. When the units 12 and 13 are thus assembled the armature plate 123 of the unit 13 completely covers the aperture 54 in the base of the unit 12 and partially covers the aperture 55 in the base of the unit 12, as clearly shown in Fig. 1.

Good nickels entering the entrance raceway 20 of the nickel unit 12 pass downward through the raceway into the raceway 23 thence into and through the raceway 26 and strike the forward face 34' of the guide portion 34 and then pass beneath the shoulder 27' thus being slowed down before they pass into the raceway 30. As a nickel passes the aperture 54 in the raceway 20 and the aperture 55 in the raceway 23 it is slowed down somewhat by the flux field produced by the magnet 120. In the raceway 30 the nickel passes between the poles of the magnets 56 and 59 and the flux field again alters the velocity of the coin according to its magnetic contents so that a good nickel enters the raceway whence it passes into the exit raceway 38.

Iron and steel disks entering the raceway 20 pass downwardly therein into the raceway 23 through which they roll to the rounded end 29 of the magnet 28. As they roll into the raceway 26 the magnet 28 attracts them into the raceway 45 through which they pass into the raceway 48 and as they fall downward in the raceway 48 they strike the abutment 52 and are guided out through the aperture 51 by the inclined abutment surface 53.

Some other non-ferrous spurious disks after passing through the entrance raceway 20 pass through the raceways 23 and 26 into the raceway 30. As these spurious disks pass through the 5 magnetic field between the poles of the magnets 56 and 59 their velocity is decreased to such an extent that as they leave the raceway 30 they do not have sufficient speed to pass over the dividing point 40 of the selector 39 so therefore fall into the raceway 41 which directs them into the raceway 42.

The raceway 38 into which good nickels are directed may communicate with a suitable coin chute which in turn will direct the nickels to the 15 coin actuated mechanism with which the device is associated. Spurious coins leaving the raceways 42 and 48 may be directed into suitable coin chutes which may either direct the spurious disks out of the machine with which the device is associated or into a suitable receiver.

Good dimes upon entering the entrance raceway 66 of the dime unit 13 pass therethrough into the raceway 68 which directs them into the raceway 72 from which they pass into the raceway 25 77 which directs them into the raceway 80. As the dimes pass from the raceway 77 into the raceway 80 they strike the shoulder 79 which momentarily stops them causing them to joggle so that each coin enters the curved section 81 of the 30 raceway 80 at approximately the same speed. As a dime passes between the poles of the magnet 120 and the armature plate 123 it passes through the flux field between the poles 121 and 122 and the armature plate 123 and is retarded sufficiently 35 so that in its fall it does not strike the dividing point 124 of the selector 107 but does not retard it sufficiently to cause it to strike the dividing point 125 of the selector 108. Thus the retardation of the dime is such that after leaving the 40 raceway 80 it falls into the raceway 87 which directs it into the exit raceway 88.

Iron and steel disks entering the entrance raceway 66 pass therethrough into the raceway 69 which directs them into the raceway 72. As they 45 roll into the raceway 72 the magnet 74 attracts them into the raceway 112 through which they roll into the raceway 116 down which they fall into the raceway 103 which directs them into the raceway 104.

Some other non-ferrous spurious disks after 50 entering the entrance raceway 66 are directed through the raceways 69, 72 and 77 into the raceway 80. As these spurious disks pass through the magnetic field between the poles of the magnet 120 and the armature plate 123 their velocity is retarded sufficiently to cause them to fall straight 55 downward into the raceway 103 and thence into the raceway 104.

The raceway 88 into which good dimes are directed may communicate with a suitable coin chute which in turn will direct the dimes to the coin actuated mechanism with which the device is associated. Spurious coins leaving the raceway 104 may be directed into suitable coin chutes 5 which may either direct the spurious disks out of the machine with which the device is associated or into a suitable receiver.

In Fig. 5 I show a sizing device which is indicated generally at 125. This sizing device includes a chute 126 through which coins pass before entering the upper end of chute 66. A member 127 is pivoted as at 128 and is provided with a weighted portion 129 so that the member normally assumes the position shown in Fig. 8. A small light weight coin entering the chute 126 will not

rock the member 127 and consequently will pass over the chute 66 and over the separating point 130 which is on the tip of the chute 67. Thus, this small light weight coin will not enter the chute 66. A proper coin however will pivot the 5 member 127 about its pivot 128 and will cause this proper sized coin to enter the chute 66 and thus pass to the coin selecting mechanism.

From the foregoing description it will be apparent that I have provided a novel coin selecting 10 device which is simple in construction and highly efficient in use.

Having thus described my invention, I claim:

1. In a coin selector, a nickel unit and a dime unit, each of said units including a base member 13 and a cover plate, the base members abutting each other and with means between each base and cover plate to form a chute, an armature plate in the base of said dime unit, a magnet opposite said armature plate, said nickel unit chute including an entrance portion communicating with a raceway therebelow, a magnet in the base of said nickel unit and a magnet in the cover plate of said nickel unit, the poles of said two nickel unit magnets being in opposed relation to each other, 20 the base of said nickel unit having an aperture therein said aperture being disposed in the portion of the base defining the nickel chute, said aperture being in alignment with said first mentioned armature plate. 30

2. In a coin selector, a pair of spaced side plates, means between said side plates to form a chute, said chute having an entrance portion and a discharge end, a pair of raceways below said discharge end of said chute, a magnet arranged adjacent to one of said raceways, said raceways being inclined away from said chute, in opposite directions, a selector member adjacent the juncture of said raceways, said selector member including a separating point, said point being positioned adjacent the bottoms of said raceways at the juncture thereof, said selector member being substantially triangular with one end pivotally mounted and having a slot at the other end and a fastening member passing through said slot to 45 retain said selector member in an adjusted position. 35

3. In a coin selector, a pair of spaced side plates, means between said side plates to form a chute, said chute having an entrance portion and 50 a discharge end, a pair of raceways below said discharge end of said chute, a magnet arranged adjacent to one of said raceways, said raceways being inclined away from said chute, in opposite directions, a selector member adjacent the juncture of said raceways, said selector member including a dividing point, said point being positioned adjacent the bottoms of said raceways at the juncture thereof, a vertical guide member forming the wall of one raceway at a side remote 55 from said point and means to loosely mount said guide member. 60

4. In a coin selector, a nickel unit and a dime unit, each of said units including a base member and a cover plate, the base members abutting 65 each other and with means between each base and cover plate to form a chute, an armature plate set in the base of said dime unit and forming a portion of one wall of said chute, a magnet opposite said armature plate, said magnet being 70 positioned in the cover plate of said dime unit and the pole faces of said magnet forming portions of one wall of said dime unit chute, said nickel unit chute including an entrance portion communicating with a raceway therebelow, a magnet in 75

- the base of said nickel unit and a magnet in the cover plate of said nickel unit, the poles of said two nickel unit magnets being arranged in opposed relation to each other, the base of said nickel unit having an aperture therein said aperture being disposed in the portion of the base defining the nickel chute, said aperture being in alignment with said first mentioned armature plate.
- 5 10 15 20 25
5. In a coin selector, a housing comprising a front member and a back member spaced apart, said housing including an entrance chute, a top guide portion and a bottom guide portion forming a raceway in communication with said chute, a second raceway sharply inclined and communicating with the first raceway and having its lower face defined by a wall terminating in a rounded point, a third raceway substantially vertically arranged and extending from the second raceway, said third raceway including an abrupt shoulder in advance of and below said rounded point, a fourth raceway in advance of the third raceway and having concentrically curved upper and lower walls with the center of curvature above the walls and with the lower wall beveled and terminating short of the end of the upper wall, a magnet member disposed in the fourth raceway, said beveled lower wall being disposed to urge coins towards said magnet, said fourth raceway

being disposed with its discharge portion directed to discharge a coin substantially horizontally, an abutment member in advance of the fourth raceway and a selecting member in advance of the said abutment member.

6. In a coin selector, a nickel unit and a dime unit, each of said units including a base member and a cover plate with means between each base and cover plate to form a chute, an armature plate set in the base of said dime unit and forming a portion of one wall of said chute, a horse-shoe magnet opposite said armature plate, said horse shoe magnet being positioned in the cover plate of said dime unit and the pole faces of said magnet forming portions of one wall of said dime unit chute, said nickel unit chute including an entrance portion communicating with a raceway therebelow, there being an aperture in said entrance portion and an aperture in said raceway, said armature plate of said dime unit covering said two apertures, a horse shoe magnet in the base of said nickel unit and a horse shoe magnet in the cover plate of said nickel unit, the poles of said two nickel unit magnets being positioned at approximately right angles to said raceway and the poles of one of said magnets being arranged in opposed relation to the poles of the other of said magnets.

WM. H. ROWE.
